UNITED STATES PATENT OFFICE.

PONTUS OSTENBERG, OF LOS GATOS, CALIFORNIA.

INTERNAL-COMBUSTION METHOD OF FORCING OR COMPRESSING FLUIDS.

1,210,679.

Specification of Letters Patent.

Patented Jan. 2, 1917.

Application filed January 24, 1916. Serial No. 73,920.

To all whom it may concern:

Be it known that I, PONTUS OSTENBERG, a citizen of the United States, and resident of Los Gatos, in the county of Santa Clara and State of California, have invented certain new and useful Improvements in Internal-Combustion Methods of Forcing or Compressing Fluids, of which the following is a specification.

- 10 My invention relates to internal combustion method of forcing or compressing fluids whereby a liquid under pressure from explosions is utilized to force or compress fluids by means of a jet or jets of said liquid.
- 15 The present invention contemplates using liquid under a high elastic fluid pressure to compress and ignite explosive mixtures, utilizing the expansions of the mixtures to force liquid into a cushion chamber, and
- 20 utilizing the liquid in a continuous stream from the cushion chamber to compress or to force fluids by a jet or jets of the liquid as will be more fully described herein.

To provide an effective and practical method of raising water from deep wells it is essential that the intricate machinery used be somewhat conveniently positioned on the surface of the ground and should, preferably, be capable of being placed at any distance from the well without materially reducing its efficiency. Also it is desirable to have the liquid being raised to flow from the discharge pipe in a continuous steady stream.

In my invention I provide a method in which liquid is subjected to a high elastic fluid pressure in a chamber provided with a substantially permanent or fixed elastic fluid cushion, and then conveyed under pressure to the desired position by means of a conduit and permitted to issue from said conduit in a jet or a series of jets, staged or compounded if necessary, in such a manner as to raise liquid any desired distance.

If liquid under pressure be discharged from an orifice near the lower end of a closed conduit immersed in a well, said discharged liquid, if directed upwardly in a jet, will tend to create a vacuum below the point of discharge and consequently raise the liquid therein. If a series of radially positioned jets be used the work done would be in proportion to the number of jets used. The effective working limit of such a series of radially positioned jets being but a few feet it is necessary to provide another series of radially positioned, upwardly directed jets at

said working limit in order to double the height to which the liquid may be raised, as liquid would be discharged from the two series of jets with equal force. By increasing the number of series of jets liquid may be raised from any depth. In the present invention I utilize a portion of the liquid under pressure to provide said jet or jets as above set forth. I also utilize a portion of the liquid under pressure to compress or force fluids by means of a jet or jets in order to replenish the supply of said liquid under pressure and thereby keep a practically uniform quantity of said liquid under pressure at all times.

One object of the present invention is also to conserve to the fullest possible extent the energy exerted by the explosion of a combustible mixture against a liquid by receiving in a chamber containing a fixed elastic fluid cushion all of the liquid thus acted upon and then utilizing the pressure exerted upon said liquid by said cushion for operating injectors as herein described.

Another advantage possessed by the present invention is that by utilizing the energy of the internal combustion of air and fuel through the medium of a jet or jets of liquid, fluids of either the liquid or gas type may be forced, as for instance, water may be forced out of wells, air may be compressed, or a vacuum may be produced, without change of the mechanism or method as will be more fully described herein.

It is, therefore, the object of my invention to provide a method whereby fluids, such as water, may be forced or raised from deep wells by internal combustion explosions generated at a distance from said water by a liquid acting in concert with said internal combustion explosions; to provide a method of the character indicated which will force or raise liquids, and compress and force air, or gases, by means of a jet or jets of liquid from a generator; and to provide a method of supplying the generator with liquid by means of liquid subjected to pressure in the generator.

In the drawings which accompany and form a part of this specification, Figure 1 is a sectional view of one means of effecting my invention, parts being broken away. Fig. 2 is a sectional view of another means of effecting my invention, parts being broken away. Fig. 3 is a sectional view showing another means of effecting my in-

vention in which two explosion chambers are used, parts broken away. Fig. 4 is a view showing means of utilizing my method for forcing water out of deep wells, part in 5 elevation, part in section. Fig. 5 is a sectional view of one means of effecting my invention in which a single compression chamber is used, parts being broken away. Fig. 6 is a sectional view on line A—A of Fig. 1. 10 Fig. 7 is a sectional detail perspective view of the diaphragm together with the instrumentalities related thereto.

Similar characters of reference refer to similar parts throughout the several views.

15 As an illustration of my improved internal combustion method of forcing or compressing fluids, I will now describe in detail the construction and operation of the mechanism shown in Fig. 1. The numeral 1 indicates a base upon which are secured low pressure chamber 2 and high pressure chamber 3, said chambers 2 and 3 being connected by conduit 4 which receives liquid from chamber 2 through check valve 5 and dis- 20 charges into chamber 3 through check valve 6. At 7 is shown a liquid supply pipe discharging into chamber 2 and receiving liquid from pipe 8 through check valve 9, pipe 8 leading to any source of supply not shown. 25 30 An injector tube 10 leads from chamber 3 into supply pipe 7 with its nozzle 11 directed toward chamber 2. At 12 is shown a casing secured to and opening into chamber 2 and having a water motor, as indicated at 13 and 35 shown in plan in Fig. 6, positioned therein in such a manner as to operate shaft 14. Shaft 14 is mounted in bearings 15 and 16 in casing 17 and is provided with a bar 18 at its upper end. Bar 18 revolves in casing 40 19 secured to the upper end of casing 17 and is provided with an electrical contact pin 20 in such a position as to alternately contact with terminals 21 and 22 respectively, positioned in the upper side of casing 19 and connected in an electrical circuit as hereinafter described. At 23 is shown a conduit connecting casing 12 and high pressure chamber 3. At 24 is shown a spring arm secured to the wall of chamber 3 and 45 having a pin 25 attached thereto in such a position as to act as a closure for the adjacent end of conduit 23 under certain conditions hereinafter set forth. The upper end of spring arm 24 is connected by a rod, 50 as 26, to the end of one arm of a bell crank 27, said bell crank 27 being pivoted as at 28 and having a valve head 29 attached to its other end in such a manner as to act as a closure for the inlet end of injector tube 10 55 when actuated by spring arm 24. At 30 is shown a diaphragm positioned in the wall of chamber 3 and actuated by the pressure produced in chamber 3 which is at all times, when the generator is in operation, greater 60 than atmospheric pressure and consequently 65

the tendency of diaphragm 30 is to expand outwardly. This tendency toward outward expansion is controlled by a set screw 31 positioned in arm 32 which is in turn secured to the wall of chamber 3 as shown. The 70 movement of diaphragm 30 is utilized by placing a pin 33 in the upper part of spring arm 24 in such a position and of such a length as to be in contact with diaphragm 30 and thereby actuate pin 25 and bell crank 75 27 as hereinafter more fully described. At 34 is provided an injector tube passing from chamber 3 to pipe 35 and having its nozzle 36 directed upwardly therein, a check valve 37 being positioned in said pipe 35 below 80 said injector tube 34 substantially as shown. The flow of liquid through injector tube 34 is regulated by valve 34^a. 34^b indicates an additional injector tube discharging into pipe 35 and provided with a regulating valve 34^c. Pipe 35 discharges into any suitable receptacle not shown, through discharge opening 35^a. At 38 is shown a cylinder having open and free communication with conduit 4. The upper portion of cylinder 38 90 forms an explosion chamber 39 into which a combustible mixture is admitted through a check valve as 40, the exhaust gases being driven out through valve 41. At 42 is shown a bracket which acts as a guide for valve 95 stem 43, with a spring as 44 positioned so as to force valve 41 to its seat. To stem 43 is secured a head as 45 having a beveled end as indicated at 46 and operating in cylinder 47, into which check valve 40 opens as shown. 100 Valve 45 is made larger in diameter than valve 41 for the purpose hereinafter described. At 48 is shown an injector tube connecting cylinders 38 and 47 and preferably discharging into the cylinder 47 at 105 an angle as shown. At 49 is shown a spark plug connected to coil 50 by high tension wire 51, coil 50 being connected to terminal 22 by low tension wire 52 through battery 53, low tension wire 54 connecting coil 50 to 110 the body of the generator as shown. If a second terminal as 21 is used it may be connected in the circuit by wire 52^a.

I will now describe the operation of the generator above described, assuming that 115 liquid has been admitted through valve 9 to a point in chambers 2 and 3 as indicated by line 55, and a fluid, as air, pumped to a pressure of say one hundred pounds in the upper part of chamber 2, through valve 56 120 and, by a similar operation producing a greater pressure, say two hundred pounds, in chamber 3 through valve 57, charges of combustible mixture having been previously introduced into combustion chamber 39. The 125 liquid in chamber 3 is now under such great pressure that diaphragm 30 is pressed outward so far as to allow pin 25 to close conduit 23 and, through the medium of rod 26 and bell crank 27, to close valve 29 as shown. 130

Injector tube 34 being the only open outlet from chamber 3 the liquid in chamber 3 is allowed to discharge from nozzle 36 in a small stream under great pressure, thereby creating a suction in pipe 35 that will draw fluid from lower depths up through check valve 37 to a point of discharge not shown. As the pressure in chamber 3 lowers on account of the discharge of liquid therefrom, diaphragm 30 moves inwardly, thus operating spring arm 24 and bell crank 27 and simultaneously permitting the discharge of liquid through conduit 23 and injector tube 10. The discharge of liquid through injector tube 10 and its nozzle 11 creates a suction in pipe 7 and thereby draws liquid from pipe 8 through check valve 9 and discharges the same into chamber 2 in sufficient quantities to compensate for the liquid drawn therefrom. At the same time the liquid passing through conduit 23 operates water motor 13 in its passage to chamber 2, the revolution of water motor 13 revolving shaft 14 and arm 18, thereby causing pin 20 to contact with, say, terminal 21. Closing the electrical circuit described generates a spark in combustion chamber 39 thus exploding the mixture contained in said chamber and driving the liquid in cylinder 38 back into conduit 4 and into chamber 3 through check valve 6. When the explosion takes place in chamber 39, the pressure against valve 45 is greater than the pressure against valve 41 because of the greater surface presented by valve 45 which is larger in diameter than valve 41. This greater pressure exerted against valve 45 serves to hold valve 41 tightly in position through the medium of stem 43 until the pressure in chamber 39 has expanded to a few pounds. As the pressure in chamber 39 decreases the pressure against the outer end 46 of valve 45 increases through the medium of injector 48 and the same is forced open against spring 44. The fine stream discharged under great pressure from injector 48 carries the combustible mixture in chamber 47 into chamber 39 at the same time drawing in additional combustible mixture through valve 40 from a carburetor not shown, and driving burnt gases out through valve 41. Since the liquid in chamber 2 is under a comparatively high pressure, said liquid will now pass through check valve 5 into conduit 4 and up in cylinder 38. Since the force of the explosion in chamber 39 has been spent, valves 45 and 41 are closed by spring 44 and consequently the rising liquid compresses the fresh charge and the same is exploded when pin 20 comes in contact with terminal 21. When valve 45 is closed chamber 47 remains filled with a combustible mixture drawn thereinto when injector 48 was in action.

The frequency of the explosions in combustion chamber 39 is governed and adjust-

ed by means of set screw 31. If set screw 31 is turned in so far as to prevent expansion of diaphragm 30 then pin 25 is held a distance away from the adjacent end of conduit 23 and liquid is forced freely through said conduit and consequently accelerates the speed of water motor 13, thus causing a more rapid succession of contacts at terminals 21 and 22. If said set screw is turned outwardly the flow through conduit 23 is lessened and the speed of water motor 13 is reduced and the succession of contacts at 21 and 22 correspondingly reduced in frequency. If, however, set screw 31 is neglected while turned in and the pressure in chamber 3 becomes too great through the rapid operation of the generator, the diaphragm 30 and the set screw 31 may both be forced outwardly because said set screw is positioned in a spring arm 32 provided for such an emergency. In this manner an excessive pressure in chamber 3 will automatically lessen the flow of liquid through conduit 23 until the pressure is reduced to such a point that spring arm 32 will again assume its normal position. Valve 29 is operated simultaneously with pin 25 for the reason that as the speed of the generator increases the more rapidly is liquid drawn from chamber 2 and consequently the more rapidly must liquid be supplied to said chamber. By means of the mechanism hereinbefore described the supply of liquid to chamber 2 is automatically and exactly proportioned to the loss therefrom.

It may now be seen that when the spark regulating mechanism and the flow of liquid through valve 34^a are properly adjusted with relation to each other the generator will be entirely automatic in its action, the induction of liquid being equal to the outflow. If the flow of liquid through valve 34^a is reduced and the pressure in chamber 3 becomes too great the generator will stop. As the pressure falls the generator will automatically resume its functions. If the flow of liquid through valve 34^a is increased and the pressure in chamber 3 falls, the generator automatically speeds up until the induction of liquid is again equal to the outflow.

Any number of injector tubes may be used in stages as 34^b in Fig. 1. When used for raising water from deep wells the injector method may be arranged as shown in Fig. 4 in which 58 is a diagrammatical representation of a generator as hereinbefore described, having a conduit 59 with a valve 60 positioned therein extending into wells 61-62 and 63 by means of branch conduits 64-65 and 66 respectively, each well having a discharge pipe positioned therein as shown at 67-68 and 69 respectively, provided with check valves 70-71 and 72 as shown and discharging into a common discharge pipe as indi-

cated at 73. Each of the branch conduits are provided with injector tubes or perforations directed upwardly and outwardly as shown at 74, and these injector tubes or perforations may be arranged in stages as indicated at 75-76 and 76^a according to the distance the water is to be raised. When the system is arranged in this manner and in full operation with discharge pipes 10 67-68 and 69 extending below the level of the liquid to be raised, the liquid is fed into conduits 64-65 and 66 under high pressure and expelled from injectors 74 75 and 76 with great force and consequently the liquid 15 in the well is sucked up through check valves 70-71 and 72 and forced out through discharge pipe 73. By this method water may be raised from any depth without excessive cost and without the intricate mechanism usually considered indispensable.

Fig. 2 shows another embodiment of my internal combustion method of forcing or compressing fluids. In this embodiment the induction of liquid into the generator is effected by means of an injector tube as 77 discharging from conduit 4 into conduit 7 as shown. This form of generator operates exactly the same as that shown in Fig. 1 except that the induction of liquid is effected directly by the pressure of explosions in chamber 39 and not by the pressure secured in chamber 3.

The two embodiments hereinbefore described and shown in Figs. 1 and 2 are of the two cycle type, but the same method may be adapted for use in a four cycle type of generator as illustrated in Fig. 3. In this embodiment conduit 4 has open communication with two cylinders as 77 and 78, cylinder 78 having combustion chamber 79 formed in its upper end which is supplied with combustible mixtures through valve 80 and exhausting through valve 81. Spark plug 82 is connected to coil 83 by high tension wire 84, coil 83 being connected to terminal 21 by wire 85 and to ground by wire 86 through battery 87. Cylinder 77 is provided with combustion chamber 88, intake valve 89, exhaust valve 90 and spark plug 91. Spark plug 91 is connected to coil 92 by high tension wire 93, coil 92 being connected to terminal 22 by wire 94 and to ground wire 86 by wire 95. To the shaft 14 of water motor 13 is connected water motor 96 in a casing 97 which is fed with liquid through supply pipe 98 from a source of supply not shown. When this embodiment is used its action is similar to that already described except that the operation of shaft 14 operates water motor 96 and thus draws water into chamber 2, and the contact of pin 20 with terminals 21 and 22 causes alternate explosions in chambers 88 and 79. The generator being in operation and assuming that combustion chamber 79 is

charged with an explosive mixture and that combustion chamber 88 is filled with liquid, the operation is as follows: The charge in chamber 79 is exploded and liquid driven therefrom and forced into pressure tank 3, exhaust valve 81 opening by force of gravity. A fresh supply of combustible mixture is now forced through valve 89 into said combustion chamber 88 thereby forcing the liquid back into chamber 79 and driving the exhaust gases therefrom through valve 81 and closing the same. The compression in chamber 2 now forces liquid through valve 5 and compresses the charge in chamber 88 which is in turn exploded. Chamber 79 being already completely filled with liquid, the liquid discharged by the explosion is forced into chamber 3. A fresh charge of combustible mixture is now forced into chamber 79 through valve 80 by any desirable method sufficient to overcome spring 99 and to force liquid back into chamber 88 and drive the exhaust gases out through valve 90 and close the same. The fresh combustible charge in chamber 79 is now compressed by liquid under pressure from chamber 2 and is exploded by means of the mechanism described.

Fig. 4 illustrates an embodiment of my invention in which but one pressure chamber is used. It differs from those forms described in that the induction of liquid into the generator is effected by an injector tube 100 discharging from chamber 3 directly into conduit 7 and thereby drawing liquid from supply pipe 8 immediately after each explosion, and the pressure for compressing a fresh charge being obtained directly from chamber 3.

It is understood, of course, that I do not wish to be confined to the definite means of effecting my improved internal combustion method of forcing or compressing fluids illustrated in the accompanying drawings and hereinbefore described, but to cover the method broadly regardless of the particular mechanisms required to effect the same.

What I claim is:

1. The method which consists in forcing liquid into a cushion chamber containing a fixed elastic fluid cushion by means of internal combustion of air and fuel, maintaining liquid in said cushion chamber at an approximately uniform pressure by means of internal combustion of air and fuel, and utilizing the liquid in a continuous stream from said cushion chamber to force or compress fluids by means of a continuous jet or jets of said liquid.

2. The method which consists in utilizing liquid under pressure of two elastic cushions, utilizing one cushion to compress explosive mixtures and the second cushion to receive the liquid forced by the explosive mixture when ignited, utilizing energy of

the generator to entrain liquid against the cushion utilized to compress the explosive mixture, and utilizing the liquid from the cushion receiving the liquid forced by the 5 explosive mixture when ignited to force or compress fluids by means of a jet or jets of the liquid.

3. The method which consists in utilizing liquid under a high elastic fluid pressure to 0 entrain liquid into a combustion chamber and compress explosive mixtures, utilizing the energy of the explosive mixtures when ignited to force liquid against the cushion which forced liquid to entrain liquid into 5 the combustion chamber, and utilizing liquid under pressure of said cushion to compress or force fluids by means of a jet or jets of the liquid.

4. The method which consists in igniting 0 and expanding a combustible mixture, causing said expanding mixture to force liquid to a high elastic fluid pressure, utilizing said high elastic fluid pressure for forcing or compressing fluids by means of a jet or jets, 5 and for forcing liquid to a lower elastic fluid pressure and utilizing said lower elastic fluid pressure for compressing a combustible mixture.

5. The method which consists in subjecting 0 one body of liquid to a low elastic fluid pressure and a second body of liquid to a high elastic fluid pressure and utilizing the difference in said elastic pressures to expel liquid, to entrain more liquid, and to compress and ignite a combustible mixture and utilizing the expanding energy of said ignited combustible mixture for maintaining a difference of pressure in said bodies of liquid.

6. The method which consists in subjecting 40 one body of liquid to a low elastic fluid pressure and a second body of liquid to a high elastic fluid pressure, utilizing the high elastic fluid pressure to expel liquid, utilizing a portion of said expelled liquid to entrain more liquid and add the same to said first body of liquid, and utilizing said low elastic fluid pressure to force liquid from said first body of liquid to said second body of liquid through the medium of gas explosions.

7. The method which consists in forcing 45 liquid into a cushion chamber by means of internal combustion of air and fuel and utilizing the liquid in a continuous stream 50 from the cushion chamber to force or compress fluids by means of a jet or jets of the liquid.

8. The method which consists in forcing 55 liquid into a cushion chamber by means of internal combustion of air and fuel, and utilizing the liquid in a continuous stream from the cushion chamber to compress or force fluids which are independent of the liquid within the generator by means of a 60 jet or jets of liquid from the cushion chamber.

9. The method which consists in forcing 65 liquid into a cushion chamber by means of internal combustion of air and fuel, conveying the liquid from the cushion chamber 70 into a well and utilizing the liquid in a continuous stream to force liquid from the well by means of a jet or jets of liquid.

In testimony whereof I have hereunto 75 affixed my signature this 15th day of January, 1916.
